UNITED STATES PATENT OFFICE.

SATTERLEE ARNOLD, OF MORRISTOWN, NEW JERSEY, ASSIGNOR TO ANNA M. ARNOLD, OF SAME PLACE.

THUMB-INSERTION MACHINE.

SPECIFICATION forming part of Letters Patent No. 392,581, dated November 13, 1888.

Application filed May 31, 1887. Serial No. 239,734. (No model.)

To all whom it may concern:

Be it known that I, SATTERLEE ARNOLD, of Morristown, county of Morris, and State of New Jersey, have invented certain new and useful Improvements in Thumb-Insertion Machines, of which the following is a full, clear, and exact description, reference being had to the accompanying drawings, and to the letters of reference marked thereon.

10 My invention has relation to a machine or apparatus especially designed for inserting thumbs or thumb-pieces in gloves or mitts, but which is applicable for insertion or union of other pieces or articles requiring like care and attention and involving like difficulties, which machine I call a "thumb-insertion machine."

15 The object of my invention is to provide or produce a simple and efficient machine or apparatus by which the part or piece to be inserted may be quickly, easily, and accurately brought to the desired size and shape, clamped and folded upon the piece or part with which it is to be connected, and then transferred to 20 a position beneath the sewing-machine needle, by which the necessary feeding and guiding are automatically regulated, in which various adjustments adapt the machine for use in connection with any thickness of material 25 and the varying sizes of gloves or like articles, and by which the desired work may be rapidly and easily performed without fatiguing the operator. To accomplish all of this my invention involves certain new and useful 30 arrangements or combinations of parts and principles of operation, as will be herein first fully described, and then pointed out in the 35 claims.

35 Thumbs or thumb-pieces have heretofore 40 been inserted in fabric gloves and mitts for the most part by the use of the ordinary sewing-machine, the operator after first securing a short section folding the edge or margin of the hole in the glove upon itself, short portions 45 at a time, then placing the folded edge upon the piece to be inserted, then advancing the two pieces thus held together under the presser-foot of an ordinary sewing-machine, and with the machine basting the two portions so 50 laid by sewing through them. Another short section is laid in like manner after the first

section has been basted, and the machine again started and the second section basted, and so on around, the machine being stopped after each section is basted and while another section is being prepared. Much delay occurs in preparing the edges accurately, (as they must be prepared,) and as the curves are very sharp the sections are necessarily very short and the stoppages of the machine frequent and many before the thumb-hole can be encircled or the basting finished. After the basting is finished the glove is turned and a row of stitching is run very close to the basting-line, or the line of juncture of the thumb and glove, and after this a second line of stitching is run a short distance from the above-named line and parallel with it, distant about an eighth of an inch. This method of "hand-insertion," as it may be called, constitutes 70 the state of the art prior to my invention.

In the accompanying drawings, forming part of this specification, Figure 1 is a plan or top view showing the clamp-plate or transfer-plate mounted in position in connection with a sewing-machine, and as if holding the material or pieces in position to be sewed together in accordance with my invention. Fig. 2 is a plan or top view of the folder by which the margin of the thumb-hole (or other opening) is turned or folded, the transfer or clamping plate being omitted. Fig. 3 is a vertical section and elevation upon a plane passing through the axis of the adjustable or sliding and vibrating bar or lever which carries the 80 clamp-plate, the parts being in position as in Fig. 1. Fig. 4 is a plan view, and Fig. 5 a side elevation, showing an oval ratchet-plate detached from the ratchet-plate shaft, and indicating the preferred manner of construct- 85 ing this plate or the ratchet-teeth thereon. Fig. 6 is an elevation of a fragment, showing the crank-shaft by which the sliding feed bar or lever is operated in position, and the mechanism by which the length or throw of the 90 crank may be varied at will, the view being upon a scale about twice that of Fig. 3; and Fig. 7 is a plan view of the under side of the disk shown in Fig. 6, representing the lever and eccentric for varying the throw of the crank. Fig. 8 is 95 a cross-section upon a plane at right angles to that of Fig. 3, and passing through the ad-

justable fulcrum upon which the feed-lever is moved, showing the eccentric for advancing or retracting the said fulcrum, so as to vary the throw or movement of the outer end of said lever, this view being also on an enlarged scale. Fig. 9 is a side elevation of the folder, and Fig. 10 a vertical section and elevation thereof. Fig. 11 is a perspective view of one of the adjustable folder-carrying plates detached from its seat and enlarged; and Fig. 12 is a view in cross-section of the same upon a plane passing through the elevating-block upon the slide, showing the screws and springs by which said block is retained in place. Fig. 13 is a section through line $x-x$ of Fig. 9, showing the multiple cam by which the folder-carrying slides are operated. Fig. 14 is a view, partly in section and partly in elevation, showing the clamp-plate upon the folder (omitting the clamping-fingers) and the margin of the opening in the material bent or turned in accordance with my invention, the thickness of the cloth being exaggerated and the view being upon a scale about twice that of Fig. 9. Fig. 15 is a plan of a fragment of the folder cover-plate, showing the clamp register-plate and thumb-size plate secured thereon, omitting the folder-carrying slides. Fig. 16 is a side elevation of the folder, showing the clamp-plate mounted thereon and in section, the clamping-fingers and former being raised and the parts in position convenient for applying the thumb-piece upon the glove or one piece upon the other. Fig. 17 is a sectional elevation showing one of the clamps or elastic clamping-fingers and the stud-cam by which it is pressed and held to its working position. Fig. 18 is a plan view illustrating a modified form of connection between the crank and the end of the sliding feed-lever.

In all the figures like letters of reference, wherever they occur, indicate corresponding parts.

The folder and the sewing-machine may be mounted upon the same bed-plate or upon the same table, if desired. The folder consists of a bed-plate, A, having a horizontal projecting portion, A', on one side, carrying two perpendicular ears, as A², to receive the horizontal axis of the former. In the center of this bed-plate is a recess to receive a many-sided cam, B. Slots are cut across the bed to receive six radially-movable folder-carrying slides, B', which fit closely in the slots and have springs a in their outer ends, which press the slides inwardly toward the center and cause them to bear against the sides or faces of the cam B. For convenience of adjusting, adjusting-screws a' are interposed between the slides and cam. Connected with a cam, B, is a lever, B², by which the cam may be moved through a short segment of a circle, and the movement of the lever B² in one direction forces the slides outward against the springs a, whereas its movement in the opposite direction permits the springs to force the slides back toward the center. A latch, as B³, is hinged to the frame

of the folder and engages and holds lever B² when moved to its greatest extent.

Attached to the inner end and on top of each slide is an elevating-block, a², which is connected with the slide by two long screws, a³ a³, rigidly attached to the elevating-block, but loosely fitting a chambered recess in the slide, so that the elevating-block can be moved up and down, but not moved laterally. A spring, as a⁴, surrounds each of the long screws a³ and acts to press the head of the screw down, thus keeping the elevating-block against the slide. An adjusting-screw, a⁵, between the screws a³ a³ and tapped or threaded into the elevating-block, presses upon the slide and serves to raise or to permit the lowering of the elevating-block when desired to vary its position to adapt it to varying thicknesses of cloth. 85

Rigidly attached to each elevating-block by suitable screws is a folder-plate, as b, which is carried high enough by the properly-adjusted elevating-block to clear the thumb-size plates and folder cover-plate referred to hereinafter, 90 and the several folder-plates project over the size-plates and folder cover-plate, so that their outer edges register nearly with the circumference of the size-plate.

The folder cover-plate C is, as shown, a rectangular plate covering the slides in the bed-plate A, to which it is secured, as by four screws, and has an irregular aperture, Fig. 15, in the center to admit the projecting elevating-blocks. It is provided with tapped or 100 threaded holes about the central opening admitting screws, as c c, by which the clamp register-plate and the thumb-size plates are secured to the cover-plate C. The clamp register-plate D, Figs. 14 and 15, is a thin oval plate 105 with an irregular opening in the center corresponding with the irregular opening in the cover-plate C, to which it is directly attached.

The clamp register-plate D, when secured to the cover-plate C, forms an annular projection by which the clamp, to be hereinafter described, is quickly registered or centered on the folder preparatory to receiving the work, and this centering or registering projection, instead of being a separate plate, as D, attached to the cover-plate, may be an annular projection, as D', (see Fig. 10,) formed directly on the said plate and integral therewith. 110 115

On top of the plate D and secured by the same screws, c c, is the thumb-size plate E, 120 which, as its name indicates, is for the purpose of determining the size of the thumb-hole. Like the clamp register-plate D, it is of thin metal and oval, though somewhat smaller, and has an irregular opening in the center corresponding with that in plate D. Supported by the ears A² A² on the bed-plate A or its extension A', and horizontally pivoted or hinged therein by pivot-screws d d, is a swinging hub, F. The former is secured to this hub by an 125 axial screw, as f, and consists of two long levers, G G, with handles G' G' on their outer or longer ends, and with adjustable stop-screws f' f' on their inner or shorter ends, which 130

screws bear against a projection, f^2 , on the hub F, to bring the levers in proper line with respect to the central line of the bed-plate A. These handles are called the "former-handles." 5 A latch, f^3 , and catch, f^4 , applied on the ends of the handles, serve to keep the levers together when closed. On the under side of the levers G G are secured by suitable screws the former-plates G^2 G^3 , the same being somewhat 10 dished downward to give room between the levers G G and clamp-plate, to be hereinafter described. These former-plates are of semi-oval form, and when attached to the levers and closed together they present an oval aperture, which accurately registers with the size-plate, around which they will loosely pass or be centered when the former-levers are brought 15 down to the size-plate. The two former-plates co-operate in bending or forming the fold in 20 the glove around the hole therein.

The clamp-plate H (of which two at least are supposed to accompany each complete machine) consists of a substantially square frame carrying four sets of ears, as h h , projecting 25 upward from the four corners. Four arms, H' , are carried by the ears h h , and have axis-bearings therein and extend radially inward or toward the center of the clamp-plate. Attached to the inner ends of each of the arms 30 H' are slotted spring-steel fingers h' , the parts of each of which, acting somewhat independently, equalize the pressure throughout the extent of their bearing. These are called "presser-fingers" or "clamping-fingers."

35 On the outer end of each of the arms H' , and close to the hub or axis, is a short projection, h^2 , under which is located a cam-stud, h^3 , the same being mounted upon the clamp-plate and near the corner thereof by use of a vertical screw, h^4 , and spring-washer h^5 , the arrangement being such that the cam-block is free to turn on its vertical axis under pressure applied to its attached lever h^6 , which is supplied for the purpose of moving it. The cam-block will not move accidentally, because of 45 the constant friction produced by the spring-washer.

On top of the cam-stud h^3 is a cam-surface, which touches the under side of the projection h^2 , and serves to forcibly raise it and thereby to depress the spring-finger h' against the clamp-plate, (or the goods or material thereon.) A portion of each of these cam-studs is cut away, so that when the stud is returned to its 50 original position the projection h^2 will clear the cam-stud, and the arm H' may then be raised, so that the work may be removed. In the center of the clamp-plate H is an oval opening, which registers with the clamp register-plate D on the folder. The margin of the opening is chamfered, so as to make it as thin as practicable and still strong enough to resist 55 springing under a pressure of the presser-fingers h' , in order that the fabric or material may 60 be held close to the bottom of the clamp-plate. I prefer to make the plate H in two parts—a

east-iron frame and a steel plate on the bottom; but it could be made solid.

On the end of the clamp-plate H are two ears, g g , having pivot adjusting-screws g' g' , 70 with check-nuts for attaching the clamp-plate to the sewing attachment. The adjusting-screws g' g' serve to make the two or more clamp-plates which should accompany each machine easily transferable from the folder to 75 the sewing attachment and easily detachable from the sewing attachment.

The clamp-plate, as above described, is servicable for various purposes, and may be used independently of the folder or of the mechanical attachment with the sewing-machine—as, for instance, it may be used to clamp pieces of fabric having ornamental designs, holding them stretched while guided by the hand, the stitching being made to follow the pattern— 85 or with an ordinary sewing-machine having the usual four-motion slip-feed the plate could be turned at will and the fabric therein or thereon being stretched would not be distorted by the feed. I do not, therefore, wish to be 90 understood as limiting my claims on this plate to combinations with the folder and sewing attachment.

The sewing-machine attachment includes an automatic feed arranged to automatically 95 guide and feed the clamp-plate in co-operation with the stitching mechanism, and a bed-plate, as I, to which the sewing-machine proper is attached, the plate projecting beyond the sewing-machine on one side to receive the parts 100 of the attachment. I' represents the main arm of an ordinary sewing-machine, and I" the needle-bar thereof. At one side of the bed-plate I is attached an overhanging bracket-arm, K, which furnishes a support and bearing for a vertical ratchet-shaft, K'.

Attached to the upper end of ratchet-shaft K' is an oval ratchet-plate, K", of such transverse and conjugate axes as to compensate for the unequal time action of the crank, or so 110 that when the crank is passing its dead-centers and its time of movement is very slow the pawl will act on a short radius and give a greater degree of rotary movement to the ratchet-plate, and when the crank is on the 115 quadrant and its time of movement most rapid the pawl will act on a long radius and give a less degree of rotary movement.

At Figs. 1 and 3 the ratchet-plate is shown as a flat metal disk having the ratchet-teeth t 120 cut in its periphery, and this form may be adopted, if desired; but I prefer to make the teeth as indicated in Figs. 4 and 5—that is, of hardened steel pins p p , projecting at right angles to the surface of the plate and located at 125 regular intervals from each other and near to the margin of the plate. These pins are inclined on their outer ends, so that the pawl will ride over each easily, and, being very hard, they will preserve their desired regularity and 130 uniformity even after long and severe usage. They are made removable from the plate, so

that in case of damage or wear any one or more can be readily detached and a perfect pin or pins quickly substituted. With the teeth cut in the margin of the plate damage to one tooth generally means damage to the entire plate. The ratchet-plate K^2 receives the motion from a pawl, as K^3 , attached to a lever, K^4 , having an adjusting-slot, so that varying degrees of throw may be provided for. The lever K^4 is actuated by connections with the cam and worm wheel (for which worm-wheel see Fig. 3) of a sewing-machine somewhat modified from that shown and described in my United States Patent No. 331,106, dated November 24, 1885.

15 The cam is so timed as to move the pawl and ratchet when the needle is out of the fabric.

On the lower end of the ratchet-shaft K' is a crank-disk, k , which disk is provided with a slot and a slide, k' , fitting therein, and an eccentric, k^2 , to adjust or move the slide, so as to vary the throw of the crank. The eccentric k^2 is moved by a lever, k^3 , which is bent upward at its outer end to receive a handle or pin, k^4 , which extends through the lever and bears 25 against the periphery of the crank-disk k . The extent of movement of lever k^3 is limited by two adjustable latches or stops, k^5 , (one on each side,) on the periphery of the disk k , so that the crank-throw may be changed instantly by the 30 operator from one extreme to the other by simply moving the eccentric-lever from one latch or stop to the other. By shifting the adjustable latches the length of the travel of the eccentric, and therefore the distance of the 35 lines of stitching one from the other, may be varied, or they may be brought nearer to or farther from the marginal line. It will be observed, of course, that this particular adjustment affects only the end or transverse axis of 40 the oval. To prevent the ratchet-shaft being turned or moved except by the designed action of the pawl and in the proper direction, so that the feeding shall always advance, and to insure against slipping or overfeeding, I provide a friction-pad or friction-brake, Fig. 6. 45 The pad is represented at k^6 , and may be made of leather, rubber, or other material which will slide easily and yet produce the necessary friction. It is arranged to bear upon the top 50 of the crank-disk k , and is mounted upon the arm K in a bent or angular support, k^7 , secured to said arm by a fulcrum-screw, as at k^8 . At k^9 is an adjusting-screw, the inturning of which will increase the pressure of the pad 55 upon the disk k , and therefore increase the friction, as will be readily seen. To reduce the friction, the screw k^9 has only to be unturned to the proper degree.

A crank-pin, k^{10} , is attached to the slide k' , 60 and connected with this crank-pin—preferably by a ball-and-socket joint, as shown—is the feed-lever L , which is mounted upon an adjustable movable fulcrum a little removed from the center and nearest the free end of the feed-lever. The fulcrum is represented at l . The feed-lever has two movements about this fulcrum—one a longitudinal reciprocating move-

ment, in which the center of movement is continually changing throughout each degree of the stroke or movement of the lever, the second an axial or pivot movement about the fulcrum or center. The end of the feed-lever opposite the crank-connection, being free, receives a movement such that any point of it will describe an oval or ellipse. The fulcrum l 70 is also provided with means for adjusting it longitudinally or in the direction of the axis of the feed-lever, so that the width or conjugate axis of the oval described by the free end of the lever may be instantly changed—in this 75 case in order to pass from one line of stitching to a parallel line of stitching—and it (the fulcrum) is also made adjustable, so that the distance between the rows of stitching may be varied or regulated at pleasure; but the adjustment might be changed with each alternate stitch, which would make zigzag sewing, and if this were extended over the edge of the fabric it would constitute overseaming, either or all of which may be desirable under 80 various circumstances. To accomplish the adjustments of the fulcrum, the fulcrum-block l' is made to fit and to slide in a longitudinal slot formed in the under side of the feed-lever L , and the fulcrum-block l' has a journal projection, which enters a bearing formed for it in a second block, l^2 , called an "adjusting-block." 85 The adjusting-block l^2 is fitted into a slot cut for it in the bed-plate I in a line drawn between the vertical ratchet-shaft K' and the 90 needle.

An eccentric, l^3 , made movable about a stud, l^4 , rigidly attached to the bed-plate I , is fitted in a recess formed for it in the adjusting-block l^2 , so that when the eccentric l^3 is moved by a 105 projecting handle, as l^5 , rigidly secured thereon, the adjusting-block is moved longitudinally in the slot of the bed-plate backward and forward, according to the direction the handle is moved, carrying the center of the fulcrum l nearer to or farther from the crank, and thereby changing the lateral throw of the opposite or free end of the feed-lever and the conjugate axis of the oval. Adjustable stops l^6 l^7 are provided and secured to the bed-plate I by 110 screws, which stops limit the throw of the eccentric-handle l^5 , one being on each side of the handle, and they serve to regulate, according to their distance from each other, the distance 115 between the rows of stitching or the distance between the peripheries of the ovals. By suitably adjusting these stops upon the bed-plate the distance of the outer row of stitching from the folded edge of the glove-hole can be regulated. Other means—as a lever extending 120 across the sliding adjusting-block—may be substituted for the eccentric for adjusting and changing this fulcrum-center; but for accuracy and convenience the eccentric is preferred.

The free end of the sliding feed-lever L is 125 provided with one rigid ear, m , and one movable latch-ear, m' , for engaging and securing the clamp-plates and guiding them by movement of the lever in corresponding ovals. In

the rigid and movable latch-ears m and m' are pivot-screws, which register and engage with the adjustable screws $g' g'$ in ears $g g$ of each of the clamp-plates H . The latch-ear m' is pivoted in a slot or recess in one side of the free end of the feed-lever L , and a spring, as m^2 , bearing against the latch-handle m^3 and against the feed-lever L , (or some projection thereon,) serves to keep the latch closed or the pivot-screw therein in bearing with the pivot-screws on the clamp-plate. By pressing on the handle m^3 of the latch the spring m^2 is compressed and the latch is opened to receive or release the clamp-plate. The adjustable pivot-screws serve to locate the clamp-plates centrally or in proper line and to render them interchangeable.

It will be apparent that as the machine is operated the ratchet-feed will move the clamp attached to the free end of the feed lever a degree for each revolution of the driving-shaft depending upon the length of the ratchet-tooth, and as the needle is operated through one reciprocating movement at each revolution of the driving-shaft it follows that as each succeeding stitch is made the clamp-plate will be moved a degree with each stitch, and will change its direction of movement with each stitch. As the direction of movement is an oval, the path of the stitching will be an oval of such axes as is determined by the length of the crank-radius and the position of the fulcrum of the feed-lever. If it be desired to change the length of the stitch, a new oval plate with ratchet-teeth of proper length can easily be substituted for the one previously used and the throw of the pawl regulated thereto.

I do not wish to confine my feed movement to the oval form of ratchet-plate above described nor to the particular mechanism by which the feeding is accomplished, for other well-known means may be substituted for describing an oval at the free end of a lever. The feed-lever might be made to slide in a sleeve and the sleeve adjusted longitudinally to change the leverage or the conjugate axis of the oval, and by well-known devices the path of the stitching can be modified by slight changes in the form of my novel sliding feed-lever. For instance, the path described by the free end of the feed-lever might be made to reciprocate by connecting the end of the feed-lever L to the crank-pin n , Fig. 18, by a transverse slot, n' , formed in the feed-lever, said lever being free to slide in a rigid sleeve, as n^2 , and still embody the novel features of my sliding feed-lever; also, the eccentric might be made to change the movement of the fulcrum-center or sleeve-case transversely to the line of sliding, instead of longitudinally, in which case any irregular curve or form could be followed by the stitching.

The automatic feeding attachment is preferably attached to the sewing-machine shown in the before-mentioned United States patent granted to me; but it may be applied to any ordinary sewing-machine, and has for its ob-

ject the receiving of the clamp-plates after the work or glove has been prepared and secured thereon, and for automatically guiding and feeding the prepared glove (or work) and clamp plates relative to the needle, so that the stitching will be made automatically in the desired line or lines and describe desired curves or forms, and so that the stitches shall be at the desired distance apart. The clamp-plates are for this purpose made detachable from the sliding feed-lever; but if the clamp-plates were to be used to hold or carry pieces of fabric with ornamental designs one could be rigidly secured to the sliding feed-lever and the pattern-plate clamped thereon without removing the plate, and still embrace the novel features of the combined clamp-plate and sliding feed-lever. The clamp-plate may be used independently of the sliding feed-lever or independently of my machine, and ornamented designs or fabrics can be stitched by use of such plates. The clamp-plates, guided by hand, could be turned readily between the feed and presser-foot of an ordinary sewing-machine, and with some fabrics, in skillful hands, even without the feed or presser-foot. So it will be seen the novel features of my clamp-plates are independent of any feed movement.

My forming and folding apparatus and clamps may also be used independently of any sewing-machine—as, for example, for inserting thumb-pieces in rubber gloves or mittens where the thumb-pieces are to be secured by cement, the fabrics being held in the clamps until the cement hardens somewhat. My forming, folding, and clamping apparatus may also be used for other purposes than inserting thumbs in gloves or mitts—as for inserting “forms” in ladies’ under-vests or for putting sleeves into undershirts or other garments. In such cases the shapes of the apertures in the clamps and other parts would be made circular instead of oval, and the clamp would in the sewing operation be guided in a circular path by well-known mechanism.

To operate my folder and sewing-machine, the fabrics are prepared apart in the folder and transferred to the sewing-machine upon the interchangeable clamp or work plate. The clamp-plate is first introduced into or upon the folder by swinging back the former-handles out of the way, and so placed thereon that the central opening will register with the central size-plate on the folder. The mitt or glove is then placed on the clamp-plate so that the thumb-hole therein is central with the size-plate. Then the latched former-handles carrying the registering former-plates are brought down, carrying the former-plate down upon the mitt or glove. A little pressure forces all that margin or fabric edge lying upon the size-plate upward and partly around the formed edges of the former-plates. To complete this turning of the fabric edge over and about the former edge to make a complete fold of the fabric edge and of the shape and form given to the former-plates, the folder-car-

5 trying slides are caused to move outwardly simultaneously by the operator through means of the cam B and attached lever-handle. (Best shown in Figs. 10 and 13.) They fold or push the upturned fabric edge outwardly and force it to bind closely down about the edge of the former-plates, as shown in Fig. 14. The latch shown secures the lever or handle and holds the slides in their outward position and the fabric edge in its folded position, while the operator, being then free-handed, can remove the former or folder plates, as before stated. The plates are made in two parts, to make their removal possible. The latch of the former-handles having been released, they can be 10 opened laterally and then swung backward out of the way without disarranging the folded fabric edge, the folders b serving to hold the edges intact. The thumb-piece, which is preferably prepared by having the side seam sewed up, may now be placed upon the outwardly-opened folders in such manner as to overlay the folded edge beneath in the relative position in which they are to be united. Quarter-sections of the thumb-piece are preferably prepared in succession and successively secured by the weight of the clamping-arms attached to the clamp-plate, which arms may be swung downward for this purpose. The folder-carrying slides may now be released and the clamps tightened by the cam-studs and the clamp or work plate transferred to the sewing-machine and attached to the guiding and feeding lever by means of the ears attached thereto 25 engaging with the pivot-screws, the latch on the guiding and feeding lever being first opened for the purpose. The guiding and feeding lever having been adjusted to describe a path coincident with the central opening in the work-plate, if the sewing-machine be started, it will sew a line of straight-ahead stitches concentric with the folded edge of fabric, which, as shown in the drawings, is of oval form or path, and this may be and is preferably the outer row of stitching. When this curve is completed, the operator, by changing the fulcrum-center by the eccentric, as shown, and the crank-radius by the eccentric adjustment, as shown, will have changed the path 30 of movement of the folded fabric edge, so that when the machine is started again the line of sewing will be in a parallel path to the previous line of sewing. When the sewing has extended around the oval, the clamp or work plate may be detached from the guiding and feeding lever, the fabric removed from the work-plate, and the work-plate introduced into or upon the folder for another preparation. 35 In using two clamp-plates I prefer two operators—one to fold and one to sew. While the operator who does the folding is preparing one clamp-plate the stitcher is sewing with a clamp-plate previously prepared, and thus the machine can be kept continuously sewing, except during the moment of detach- 40

ing the clamp-plate and introducing another made ready for the purpose.

Much more and better work can be accomplished by my automatic guiding, feeding, and sewing mechanism than by hand, for, the guiding being automatic, the operator can run the machine at full speed without any attention to the guiding, whereas in hand-work all the guiding is done by hand and eye of the operator and the speed is necessarily very limited. A great gain in rapidity is also secured by use of my automatic folder, as by a few successive movements of the folder by the operator the edge of the thumb-hole is turned or folded at once, whereas by the process heretofore followed the operator has by hand to successively fold short sections of the thumb-hole edge, and this cannot be done with any degree of accuracy approaching that of the machine-folding. 85

Having now fully described my invention, what I claim as new herein, and desire to secure by Letters Patent, is—

1. In a fabric folding and holding apparatus, the combination of a former consisting of horizontally-separable plates curved to provide an entirely-enclosed opening (when the said plates are together) of the form of the fabric edge to be folded, and a sectional clamp having curved spring clamping plates or fingers collectively 95 similar in form to the opening afforded by the plates of the former.

2. In a fabric folding and holding apparatus, the combination of two former or folding guide-plates having curved portions to provide an 100 entirely-enclosed opening of the shape of the fabric edge to be folded, said plates being pivoted vertically, so that they may be brought together or separated horizontally, as described, and a sectional clamp having curved 105 spring clamping plates or fingers to bear on the former-plates around the opening thereof.

3. In a fabric folding and holding apparatus, two former-plates having curved portions to provide an entirely-enclosed opening of the 110 shape of the fabric edge to be folded, said plates being pivoted so that they may be brought together or separated, combined with a latch for securing the said plates together when desired, and with a clamp having curved clamping 115 plates or fingers to bear around the opening of the said former-plates.

4. In a fabric folding and holding apparatus, the combination, with a clamp, of two former-plates having curved portions to form an en- 120 tirely-enclosed opening, a hub or plate having a horizontal pivot and to which the arms or rear portions of the said former-plates are vertically pivoted, whereby the said former-plates are adapted to be raised and lowered and 125 to be swung in and out horizontally, to enable the clamp to be placed upon or removed from the folding device.

5. In a fabric folding and holding apparatus, the combination, with two vertically-pivoted 130 or horizontally-swinging former-plates having curved portions to form an entirely-in-

closed opening of the shape of the fabric edge to be folded, of stops for centering the said plates when they are brought toward each other, and a clamp having curved clamping plates or fingers to bear around the opening of the said former plates.

6. In a fabric folding and holding apparatus, the combination, with a clamp having curved clamping plates or fingers, of former-plates having curved portions to form an entirely-inclosed opening, a series of radially-movable folder-carrying slides having folder-plates extending horizontally above the edges of the said former-plates, and means for supporting and simultaneously operating the said slides.

7. In a fabric folding and holding apparatus, the combination, with a clamp having curved clamping plates or fingers, of former-plates having curved portions to form an entirely-inclosed opening, a series of radially-movable folder-carrying slides having folder-plates extending horizontally above the edges of the said former-plates, a cam and hand lever for simultaneously forcing the said slides outward, and a series of springs for retracting the same.

8. The combination, with the former-plates and the clamp, of the radially-movable slides B', and means for supporting and operating the same, each of the said slides being provided with a horizontally-projecting and downwardly spring-pressed folder-plate, b.

9. The combination, with the former-plates and the clamp, of the radially-movable folder-carrying slides B', the supporting-plate A, and means for simultaneously operating said slides, each of the said slides having a riser or block, a', carrying a folder-plate, b, and being provided with screws a', having surrounding springs a'.

10. In an apparatus for folding and holding fabrics, the combination, with a clamp and the former-plates, of the radially-movable folder-carrying slides B', the supporting-plate A, the cam B, the lever B', and the latch B'.

11. In an apparatus for folding and holding fabrics, the combination, with a clamp having spring clamping plates or fingers, of a former consisting of horizontally-separable plates having curved portions to provide an inclosed opening, a clamp-support, as plate C, having an opening, and a clamp register plate or projection, as D, on said support around said opening.

12. In an apparatus for folding and holding fabrics, the combination, with a clamp and two separable former-plates having curved portions to provide an inclosed opening, and over which portions the edge of the fabric is to be folded, of a size-plate having a contour which is of the form and shape of the opening left in the fabric or article when the fabric edge is folded over.

13. The combination, with the clamp and the former plates, of the plate C, having an opening or aperture, a clamp registering plate or annular projection thereon surrounding the

said aperture, and the thumb size plate E, superposed on the said clamp registering plate or projection.

14. The combination, with an apparatus for folding over the edge of an opening in a fabric or a tubular article of fabric, of a flat clamp-plate entirely disconnected from the folding apparatus and having an inclosed opening, a series of clamping arms or levers pivotally supported on the said clamp-plate, and curved clamping plates or fingers carried by the said arms or levers, and serving, collectively, to surround the opening of the said clamp-plate.

15. A flat clamp plate having an inclosed opening, combined with a series of pivoted clamping arms or levers, curved spring clamping plates or fingers carried by the said arms or levers and of proper form, collectively, to surround the said opening, and means for holding said clamping-plates in clamping position.

16. A flat clamp-plate having an inclosed opening, combined with a series of pivoted clamping-levers supported by said plate, and having curved spring clamping plates or fingers of proper form, collectively, to surround said opening, and a series of handled cam studs or blocks for holding the said clamping plates or fingers in operative position.

17. A flat clamp-plate having an inclosed opening, combined with two or more independently-operating spring clamping arms or levers arranged around said opening, and having curved clamping plates or fingers serving, collectively, to surround said opening.

18. The combination, with a stitch-forming mechanism and a clamp-plate feeding mechanism comprising a guiding feed-lever, and means for operating the same, of a clamp-plate provided with clamping arms and plates, and having lugs or ears by which it may be quickly connected with or detached from the said feed-lever.

19. The combination, with a stitch-forming mechanism and a work-clamp, which is detachable from the sewing-machine, of a horizontal guiding feed-lever having a fulcrum between its ends and detachably connected at its forward end with said work-clamp, a rotary crank pin or device engaging the rear of said lever to operate the same, and a vertical rotary shaft to actuate said crank pin or device to cause said clamp to be moved in any desired path beneath the sewing-machine needle.

20. The combination, with a stitch-forming mechanism, of a work-clamp, a guiding feed-lever to which the said clamp is attached, an adjustable crank-pin for operating said lever, means for operating said crank-pin, and an adjustable fulcrum for the said feed-lever, whereby the said clamp may be moved in a circular or elliptical path which may be varied to sew parallel and concentric rows of stitches.

21. The combination, with a stitch-forming mechanism, a guiding feed-lever, and operating mechanism for the latter, of a work-clamp having ears or lugs, and the said lever having a pivoted latch or lever to enable the ears

of the said clamp to be quickly connected with or detached from the said lever.

22. The combination, with the stitch-forming mechanism and the work-clamp having 5 ears g , of the guiding feed-lever L and means for operating the latter, the said lever being provided with the stationary and movable ears m and m' , and with the handle or lever m'' , by which the latter ear is carried.

23. The combination, with a stitch-forming mechanism, of a work-clamp, a guiding and feeding lever for the said clamp, an adjustable crank-pin for operating said lever, means for actuating said crank-pin, an adjustable fulcrum for the said feed-lever, levers or arms for shifting said fulcrum and crank-pin, and stops for limiting the movements of the said levers or arms in both directions.

24. The combination, with a work-clamp and 25 a stitch-forming mechanism, of a guiding feed-lever detachably connected at one end with the said clamp, a shaft having a crank-pin connected with the other end of said lever, a ratchet feed plate or wheel on the said shaft provided with removable pins, and means for operating said ratchet feed-plate.

25. In a fabric folding and holding apparatus, the combination, with a clamp-holding

support and a former-plate having an edge of the shape of the fabric edge to be folded, of a 30 clamp entirely disconnected from said support, and having plates or fingers to hold the folded edge, arranged to correspond to the shape of the edge of the said former-plate, the said former-plate being removable from the said clamp to 35 permit the latter, with the folded fabric held therein, to be taken from the said clamp-holding support.

26. The combination, with a folding apparatus consisting of former-plates and a series 40 of radially-movable folder-carriers having at their outer ends folders to extend over the said former-plates, of a clamp which is entirely disconnected from the bed plate or support of the said folding apparatus, so that the 45 said clamp, with the folded and prepared work therein, may be removed from the folding apparatus when the folding and preparing operation is completed.

In testimony that I claim the foregoing I have 50 hereunto set my hand in the presence of two witnesses.

SATTERLEE ARNOLD.
